ILLUMINABLE VANITY MIRROR

William A. Folger, Toledo, Ohio, assignor to Lighting Products, Inc., Toledo, Ohio, a corporation of Ohio

Filed Oct. 28, 1968, Ser. No. 14,207

Term of patent 14 years

Int. Cl. D28—03

U.S. Cl. D86—10

FIG. 1 is a front perspective view of an illuminable vanity mirror showing my new design, the back of the mirror being conventional;

FIG. 2 is an enlarged front elevational view thereof with the mirror in a slightly tilted position; and

FIG. 3 is a side elevational view from the right of FIG. 2.

I claim:

The ornamental design for an illuminable vanity mirror, substantially as shown and described.
